UNITED STATES PATENT OFFICE.

FRIEDRICH GRAFFENBERGER, OF MILWAUKEE, WISCONSIN.

COLLAPSIBLE BOX.

Application filed June 15, 1922. Serial No. 568,554.

To all whom it may concern:

Be it known that I, FRIEDRICH GRAFFENBERGER, a citizen of the United States, residing at Milwaukee, in the county of Milwaukee and State of Wisconsin, have invented certain new and useful Improvements in Collapsible Boxes, of which the following is a specification, reference being had to the accompanying drawing, forming a part 10 thereof.

The main objects of this invention are to produce a folding or collapsible one-piece box for various uses, having reinforced corners which when the box is set up will be 15 firm and stable; to facilitate setting up or erecting and collapsing such boxes; to economize material in the production thereof; to provide simple easily manipulated fastenings which are connected with the 20 boxes so that they are always available for holding the covers securely closed, thereby dispensing with string or other extraneous means for the purpose; and generally to improve the construction and increase the 25 utility of boxes of this type.

It consists in the construction, arrangement and combination of parts as herein-after particularly described and pointed out in the claims.

30 In the accompanying drawing like characters designate the same parts in the several figures.

Figure 1 is a plan view of a collapsible box embodying the invention, knocked down 35 and spread flat, in condition for storage and transportation in small compass; Fig. 2 is a perspective view of the box set up in condition for use, with the cover open; Fig. 3 is a similar view of the box closed; Fig. 4 is 40 a cross section on the line 4-4, Fig. 3; and Fig. 5 is a longitudinal section on the line 5-5, Fig. 3.

Referring to Figs. 1, 2 and 3, the box, which may be made of any suitable material 45 such as heavy paper or pasteboard, comprises a bottom member 1, side members 2 and 3, end members 4, and a cover member 5, formed integrally with one another from a single sheet of material. The bottom, side 50 and cover members are connected with one another on parallel folding lines, which are preferably scored or creased to facilitate

folding, as indicated by dotted lines 6 in Fig. 1. The end members or sections 4, are connected with the bottom member or section 1 on folding lines 7 at right angles to the lines 6, and preferably creased or scored to facilitate folding. 55

The end members 4 are each formed adjacent their ends with two angular locking 60 slits 9 mainly transverse to the folding lines 7, and the side members 2 and 3 are extended at the ends beyond the score lines 7 and formed into hooked tabs 10, adapted when the box is erected to be folded inwardly over or outside of the end members 4 and tucked through the slits 9 into interlocking engagement with the end members, as shown in Fig. 2, the tabs being severed from the adjacent ends of the end members 70 4, and creased or scored along the lines 7, to facilitate folding them inwardly over the end members. 75

The cover member 5 is formed at the ends with flaps 12, adapted to fold downwardly 80 along the score lines 7 over the end members 4 and provided at the ends with downwardly extending tongues 13, which when the box is set up and the cover closed, are inserted between the end members 4 and 85 the corner tabs 10 as shown in Fig. 3, thereby reinforcing, and staying the corners of the box. Between the tongues 13 the flaps 12 overlap the upper offset ends of the slits 9 and the upwardly 90 projecting points of the tab hooks inserted therein, thereby securely holding the hooked tabs in interlocking engagement with the end members 4 and further contributing to the firmness and stability of the box ends 95 and corners.

For fastening and holding the cover member 5 closed, as shown in Fig. 3, the side member 2 is formed or provided with one or more straps adapted to be folded inwardly over the cover member as shown in Fig. 3, and formed with enlarged arrow- or T-shaped heads 15, adapted for interlocking and releasable engagement with U-shaped slits 16, formed in the cover member. 100

To stiffen the edge of the side member 2, to which the fastening straps are attached, and to close the joint between it and the cover member when the box is closed, the

side member is preferably formed, as shown in Figs. 1 and 2, with an inwardly folding flap 17, from which the fastening straps are severed at the sides when they are formed integrally with the box.

The box as thus far described, is adapted for containing and carrying various articles such as clothing, and may be made in different sizes and of various dimensions.

10 As shown in the drawing, it is particularly designed for holding and candling or inspecting eggs or other articles, such as certain kinds of candies which it is desirable to keep out of contact with one another for 15 preventing breakage or injury.

For this and similar purposes, the bottom and the cover members 1 and 5 are either or both formed with adjustable or yielding partition leaves or members 18, which are 20 bent obliquely and oppositely inward so as to embrace and hold between them and the adjacent side members 2 and 3 eggs, as indicated by dotted lines in Figs. 4 and 5, or other fragile articles which it is necessary 25 or desirable to separate from one another. The partition leaves or members 18 are severed from one another and from the box member or members to which they are attached, preferably on transverse lines 19,

30 and intersecting diagonal or oblique lines 20, and are folded inwardly on diagonal or oblique lines 21, which are preferably creased or scored, thereby forming diamond-shaped openings 22, through which eggs or 35 other articles contained in the box are exposed to view.

Each pair of obliquely and oppositely infolded yielding leaves 18, diverge from each other towards the adjacent side member 2 40 or 3, and two oppositely located pairs of such leaves, make, with said side member, an elastic pocket or compartment, conformable to eggs or other things of varying size and shape.

45 For holding and inspecting eggs, the openings 22 are located in the bottom and cover members of the box or case opposite one another, so that the light from a candle or other source will pass through the individual eggs contained in the box or case, and the operation of testing the eggs by candling is thus greatly facilitated.

Various modifications in the minor details of construction and arrangement of parts of 55 the box to adapt it to the various uses for which it is intended and suitable, may be made without departure from the spirit and scope of the invention as defined in the following claims.

60 I claim:

1. A collapsible box comprising integrally formed bottom, side, end and cover members, the end members each formed with two transverse slits, the side members formed with hooked tabs adapted to fold over the

end members and to interlock with the slits therein, and the cover member formed with end flaps adapted to fold over the end members and provided with tongues adapted to pass in closing between the end members 70 and the tabs and to stay the corners of the box.

2. A collapsible box comprising integrally formed bottom, side, end and cover members, the side and end members formed with 75 interlocking corner tabs and slits, the cover member formed with a slit and one side member provided with a strap foldable over the cover member and having an enlarged head adapted for interlocking engagement 80 with the slit in the cover member to hold it closed.

3. A collapsible box comprising integrally formed folding bottom, side, end and cover members, the side and end members formed with interlocking corner tabs and slits, the cover member formed transversely to its 85 free edge with locking slits and the side member opposite that to which the cover is integrally attached having an infolding flap 90 and a T-headed strap severed at the sides therefrom and adapted for interlocking and releasable engagement with the slits in the cover member.

4. A collapsible box comprising integrally 95 formed folding bottom, side, end and cover members, the side and end members formed with interlocking corner tabs and slits, the cover member formed adjacent and transversely to its free edge with a number of 100 pairs of locking slits and the adjacent side member formed at its upper edge with a flap adapted to fold inside of the cover and with locking straps severed at the sides from the flap and having enlarged heads adapted 105 to fold over the cover and to interlock with the slits therein.

5. A collapsible box comprising opposite members provided with obliquely and oppositely infolded yielding leaves, two oppositely located pairs of such leaves forming 110 an elastic compartment.

6. A collapsible box comprising opposite members provided with oppositely and obliquely infolded yielding leaves cut therefrom and forming opposite sight openings 115 therein, each pair of such leaves diverging towards an adjacent side member, and two oppositely disposed pairs of leaves forming with said side member, a conformable elastic 120 compartment.

7. A collapsible box comprising a bottom member provided with side and end members at opposite edges thereof and a cover member connected to one of said side members, the adjacent ends of said side and end members being provided with interlocking tabs and slits, said cover member being provided at opposite ends thereof with flaps 125 having tongues adapted and arranged to re- 130

inforce the corners of said box and to co-operate with said tabs to hold the latter in interlocking relation with said slits.

8. A collapsible box comprising a bottom member provided with side and end members at opposite edges thereof and a cover member connected to one of said side members, each of said end members being provided with parallel transverse slits, said side members being provided at the ends thereof with tabs adapted and arranged to interlock with said slits, said cover member being provided at opposite ends thereof with flaps having tongues adapted and arranged to reinforce the corners of said box and to cooperate with said tabs to hold the latter in interlocking relation with said slits.

9. A collapsible box comprising a bottom member provided with side and end members at opposite edges thereof and a cover member connected to one of said side members, said side and end members being provided at adjacent ends thereof with means for holding said members in assembled relation, and means adapted and arranged to hold said cover member in closed position and to close the joint between the same and the corresponding side member, said means

comprising a flap formed integrally with one of said members and adapted to be folded inside of said box, and a lock comprising a strap formed integrally with one of said members and adapted and arranged for insertion through a slit with which the other of said members is provided.

10. A collapsible box comprising a bottom member provided with side and end members at opposite edges thereof and a cover member connected to one of said side members, said side and end members being provided at adjacent ends thereof with means for holding said members in assembled relation, and means adapted and arranged to hold said cover member in closed position and to close the joint between the same and the corresponding side member, said means comprising a flap formed integrally with said side member and adapted to be folded inside of said box, and a lock comprising a strap having a portion thereof cut from said flap, said cover member being provided with a slit arranged to receive said strap.

In witness whereof I hereto affix my signature.

FRIEDRICH GRAFFENBERGER.
